POLYMERIZABLE ESTERS OF ALPHA-SULFONATED FATTY ACIDS

Raymond G. Bistline, Jr., Philadelphia, William S. Port, Norristown, Alexander J. Stirton, Philadelphia, and James K. Weil, North Wales, Pa., assignors to the United States of America as represented by the Secretary of Agriculture

No Drawing. Application June 24, 1955
Serial No. 517,953

6 Claims. (Cl. 260—400)

(Granted under Title 35, U. S. Code (1952), sec. 266)

A non-exclusive, irrevocable, royalty-free license in the invention herein described, throughout the world for all purposes of the United States Government, with the power to grant sublicenses for such purposes, is hereby granted to the Government of the United States of America.

This invention relates to monomeric and polymeric olefinic esters of α -sulfonated long-chain fatty acids.

An object of this invention is to provide novel compositions having improved surface-active, emulsifying and detergent properties. Another object is to provide novel polymers having emulsifying and detergent properties and also being useful as water-soluble thickening agents. Other objects will appear hereinafter.

According to the invention, esters corresponding to the formula

wherein R is an alkyl group of 10 to 20 carbon atoms and M is Na, K, Li, or NH_4 , not only have valuable surface-active, emulsifying and detergent properties but are readily polymerized to yield polymers having similar properties and, in addition, being useful as thickeners for aqueous solutions. For example, a mixture containing water, an oil such as mineral oil, and such a polymer, as for instance polymerized sodium allyl α -sulfopalmitate and polymerized sodium allyl α -sulfostearate, as an emulsifying agent, forms a stable emulsion.

The fatty acids useful in making our esters are the saturated aliphatic acids of 12 to 22 carbon atoms. Those having less than 12 carbon atoms yield esters deficient in surface-active properties while those having more than 22 yield esters have only very limited solubility in water. The optimum balance between the hydrophilic and hydrophobic properties of the esters is obtained when fatty acids of 16 to 18 carbon atoms are used. This is a fortunate circumstance because the saturated fatty acids available in greatest abundance at lowest cost are palmitic and stearic acids. Of course it is to be understood that it is not necessary or desirable to use a single pure acid and that in general the most suitable acid material is the crude acid or mixture of acids obtainable from the more saturated fractions of lard, tallow, grease, cottonseed oil and similar glycerides or from these same fats after hydrogenation.

The monomeric esters of the invention may be made by any of the known procedures for esterifying α -sulfo-carboxylic acids, a convenient one being simply heating the sulfoacid with allyl alcohol, preferably under conditions such that the water formed is continuously removed during the esterification. While other unsaturated aliphatic alcohols, such as chloroallyl, methallyl or crotyl alcohol or methyl vinyl carbinol, may be used to esterify the sulfoacids, the results are in general unsatisfactory. Hence we prefer to use allyl alcohol.

2

The monomeric allyl esters are readily polymerized by the usual free radical processes, such as warming with an organic peroxide or a per-salt, irradiation with ultraviolet light or by use of a redox catalyst system.

6 The invention is illustrated by the following examples.

EXAMPLE I

Preparation of allyl α -sulfo-esters

10 A solution of 0.357 mol of α -sulfopalmitic acid in 500 ml. of allyl alcohol was refluxed, with stirring, for 20 hr. After being cooled and neutralized with sodium hydroxide, the reaction mixture was refrigerated at -27°C ., thus causing the precipitation of crude sodium allyl α -sulfopalmitate in 85% yield and of a purity entirely suitable for use in surface-active or detergent compositions.

15 By repeated crystallization of the crude product from methanol, water, and a mixture of methanol and acetone, the pure compound was obtained as a white powder, M. P. 92.2–93.4° C., and containing 56.9% C, 8.85% H, 5.68% Na and 8.12% S. Its iodine number was 61.1. The corresponding theoretical values are 57.3, 8.88, 5.77, 8.05 and 63.7, respectively.

20 25 By using α -sulfostearic acid instead of the α -sulfopalmitic acid used above, a 90% yield of crude sodium allyl α -sulfostearate was obtained. Repeated recrystallization yielded the pure compound as a white powder, M. P., 99.2–100.5° C., containing 59.0% C, 9.14% H, 5.39% Na, and 7.40% S. Its iodine number was 58.9. The corresponding theoretical values are 59.1, 9.21, 5.39, 7.52 and 59.5 respectively.

25 30 Similarly, other α -sulfonated fatty acids having 12 to 22 carbon atoms are esterified with allyl alcohol and then neutralized with a suitable base to yield products of the same general nature.

35 The K, Li, or NH_4 salts of the allyl α -sulfo-esters are readily obtained by neutralizing the sulfonic acids with the corresponding hydroxide or carbonate and they in 40 general have the valuable properties of the sodium compounds.

EXAMPLE II

Polymerization of allyl esters

45 50 The monomeric esters of Example I were polymerized by dissolving 75 g. of monomer and 3.5 g. of potassium persulfate in 700 ml. of water and heating the solution at 70°C . for 8 hr. The progress of the polymerization was evident by increase in viscosity during this period.

55 After 3 hr. of heating the solutions were too viscous to be stirred effectively.

The polymers were precipitated by the addition of 2100 ml. of 95% ethanol, redissolved in water and again precipitated by the addition of 2 volumes of alcohol. After two more reprecipitations the polymers were dried in a vacuum oven and thus obtained as light cream colored powders in yields of about 70%.

Properties of monomeric allyl esters

60 65 All the monomeric esters were readily soluble in soft, hard or sea water. Solutions containing as much as 20% of ester became very viscous or gelled on standing. Aqueous solutions were highly stable to most metallic ions, such as Ca^{++} , Mg^{++} , Fe^{++} , Ni^{++} , Cu^{++} and Zn^{++} , and were effective surface-active, foaming and wetting agents having excellent emulsifying and fair detergent properties. The latter were greatly improved by use of conventional builders. In contrast with most esters, and in particular, esters of carboxylic acids not having an α -sulfo group, the esters of this invention were highly stable to hydrolysis in aqueous solution even in the presence of acid or base. This unexpected property makes

these esters of particular value for use as surface-active, wetting and foaming agents, emulsifiers and detergents.

Properties of the polymeric allyl esters

The polymeric esters dissolved in soft, hard or sea water to form viscous, thixotropic solutions. Thus, a 2% aqueous solution of polymeric sodium allyl α -sulfopalmitate at 25° C. had viscosities of 36.8, 23.8, 14.3 and 10.8 poises as measured with a Brookfield synchroelectric viscometer, using a Number 3 spindle at 6, 12, 30 and 60 R. P. M. respectively. Such aqueous solutions were stable to most metallic ions and, like the monomers, were resistant to hydrolysis. The polymers showed little effect on the surface and interfacial tension of water and had only slight foaming and wetting properties. They showed only fair detergent activity but were extremely effective emulsifying agents.

The emulsifying properties of both the monomers and the polymers were determined by a method of intermittent violent shaking [Briggs, J. Phys. Chem., 24, 120 (1920); Martin and Herman, Trans. Faraday Soc., 37, 25 (1941)]. A stoppered 500 ml. Erlenmeyer flask containing 40 ml. of refined mineral oil and 40 ml. of a 0.1% aqueous solution of the material being tested was manually shaken in 5 violent downward motions and then allowed to stand 1 minute. This was repeated 5 times, after which the emulsion was poured into a 100 ml. graduated cylinder and the time required for the separation of 10 ml. of the aqueous phase was noted. This was a measure of the stability of the emulsion and the effectiveness of the emulsifying agent. Results are shown in the following table.

TABLE I.—EMULSIFYING PROPERTIES

Emulsifying agent:	Time, sec. ^a
Na allyl α -sulfopalmitate	160
Na allyl α -sulfostearate	320
Polymeric Na allyl α -sulfopalmitate	11,600
Polymeric Na allyl α -sulfostearate	5,550
Na alkylbenzenesulfonate ^b	180
Polyoxyethylene sorbitan trioleate ^b	120

^a Time for separation of 10 ml. of aqueous phase.

^b Commercial emulsifying agents.

The other monomeric and polymeric esters of this invention have emulsifying properties similar to those shown in the above table.

We claim:

1. A polymer of a compound having the formula

10 wherein R is an alkyl group of 10 to 20 carbon atoms and M is a member of the group consisting of Na, K, Li, and NH₄.

2. Polymerized sodium allyl α -sulfopalmitate.

3. Polymerized sodium allyl α -sulfostearate.

15 4. A stable emulsion comprising water, oil and a polymer of a compound having the formula

20 wherein R is an alkyl group of 10 to 20 carbon atoms and M is a member of the group consisting of Na, K, Li, and NH₄ as the emulsifying agent.

25 5. A stable emulsion comprising water, oil and polymerized sodium allyl α -sulfopalmitate as the emulsifying agent.

6. A stable emulsion comprising water, oil and polymerized sodium allyl α -sulfostearate as the emulsifying agent.
